UNITED STATES PATENT OFFICE.

JAMES H. GILL, OF STEUBENVILLE, OHIO.

DESIGN FOR A RADIANT FOR GAS STOVES.

Application filed June 4, 1929. Serial No. 31,539. Term of patent 7 years.

To all whom it may concern:

Be it known that I, JAMES H. GILL, a citizen of the United States, residing in Steubenville, in the county of Jefferson and State of Ohio, have invented a new, original, and ornamental Design for Radiants for Gas Stoves, of which the following is a specification, reference being had to the accompanying drawing, forming part thereof.

In the drawing:

Figure 1 is a perspective view of a radiant embodying my new design.

Figure 2 is a front elevation thereof.

I claim:

The ornamental design for a radiant for gas stoves as shown.

In witness whereof, I have hereunto set my hand.

JAMES H. GILL.
